ELECTRODE MOUNTING FOR NEON TUBES

Frank Kaspar, Cicero, Ill., assignor to General
Scientific Corporation, Chicago, Ill., a corpora-
tion of Illinois

Application October 10, 1938, Serial No. 234,147

6 Claims. (Cl. 176—126)

The present invention relates to gaseous conduction devices, and more particularly to the mounting of electrodes in the ends of gaseous conduction tubes which are utilized for display signs and the like.

In the past there has been considerable difficulty in the processing of the tubes because of the fact that the lead-in wires often fail, due to the extremely high heat in the processing and, if the electrode is supported by the lead-in wires, the hot electrode strikes the glass of the tube and breaks it. It is also important in shipping and in operation to have the electrodes so mounted that they may be prevented from contacting the tube walls. Reentrant stems on the glass tube itself and various other devices have been employed to properly support the electrode. It has also been proposed to enclose the electrode in a glass shield to prevent it from contacting the glass, and other practices include the provision of some sort of insulating ring, such as a ring of glass beads or a collar adjacent both ends of the electrode, the beads or collar serving the purpose of supporting the electrode while they in turn are supported by the wall of the glass tube.

It is the purpose of the present invention to provide a more simple, economical and effective supporting means by which the electrode can be carried on the lead-in wire and be prevented from engaging the walls of the surrounding tube.

The features and advantages of the present invention will appear more fully as the description proceeds, reference being had to the accompanying drawing wherein a preferred form of the invention is shown. It is to be understood, however, that the drawing and description are illustrative only, and are not to be taken as limiting the invention except insofar as it is limited by the claims.

In the drawing, Fig. 1 is a view in side elevation of the electrode and of a gaseous conduction tube embodying my invention;

Fig. 2 is a longitudinal section taken on the line 2—2 of Fig. 1, and

Fig. 3 is a sectional view taken on the line 3—3 of Fig. 2.

Referring now to the drawing, the numeral 5 designates the electrode end of a gaseous conduction tube. An electrode 6 is mounted in the tube 5. The electrode 6 has one end closed, as indicated at 7. This end of the electrode is utilized to support the electrode in the tube 5. A doubled lead-in wire 8 is employed, the lead-in wire being fastened at 9 to the end of the elec-

trode 6 and having its leg portions 10 and 11 spread apart at a short distance from the end of the electrode 6.

A cup-shaped insulating member 12 fits over the rounded end of the electrode 6 and is held in place by the lead-in wire 8. The member 12 has an opening 13 through which the lead-in wire extends, and the member 12 is supported by the lead-in wire, due to the spreading of the portions 10 and 11. The member 12 is slightly larger in internal diameter than the external diameter of the electrode 6. It covers only about $\frac{1}{4}$ of the exterior surface of the electrode 6. The exterior surface of the member 12 is cylindrical between the points 14 and 15 (see Fig. 2) and the exterior diameter of the member 12 is such that this cylindrical portion fits loosely inside the tube 5. The amount of play between the tube and the member 12 is sufficient to avoid binding, due to differences in expansion and contraction. However, the cylindrical part of the member 12 prevents tipping of the member in the tube an amount sufficient to permit the electrode 6 to engage the tube 5. This is clearly shown in Figs. 2 and 3, wherein the limit of movement of the electrode 6 toward the glass tube 5 is illustrated.

It is believed to be evident that the present invention provides a means whereby the electrode is held away from the wall of the tube, even during bombardment and processing of the tube, whether or not the lead-in wires fail. It is, of course, evident to those skilled in the art that the member 12 also provides effective protection for the lead-in wires by substantially insulating the lead-in wires against discharge exteriorly of the electrode. The spaces between the member 12 and the tube 5 and between the member 12 and the electrode 6 are so small as to substantially provide mean free path insulation.

From the above description it is believed that the construction and advantages of this device will be readily apparent to those skilled in this art. Having thus described my invention, what I claim as new and desire to secure by Letters Patent is:

1. The electrode end of a gaseous conduction tube, comprising a length of glass tubing closed at one end, a tubular electrode in said tube, a lead-in wire having two branches which are secured to said electrode and a cup-shaped insulating member covering the lead-in wire end of the electrode, said cup-shaped member being held in position on the electrode by said branches of the lead-in wires.

2. The electrode end of a gaseous conduction tube, comprising a length of glass tubing closed at one end, a tubular electrode in said tube, a lead-in wire having two branches which are secured to said electrode and a cup-shaped insulating member covering the lead-in wire end of the electrode, said cup-shaped member being held in position on the electrode by said branches of the lead-in wires, said cup-shaped member having a cylindrical portion the exterior and interior surfaces of which loosely fit the corresponding surfaces of the tubing and electrode respectively, whereby tilting of the electrode into engagement with the tubing is avoided.
- 5 3. The electrode end of a gaseous conduction tube, comprising a length of glass tubing closed at one end, a tubular electrode in said tube, a lead-in wire having two branches which are secured to said electrode and a cup-shaped insulating member covering the lead-in wire end of the electrode, said cup-shaped member being held in position on the electrode by said branches of the lead-in wires, said cup-shaped member having an opening in the base thereof through which the 10 branches of the lead-in wire extend, said branches being turned out directly outside of said opening.
- 15 4. In a gaseous conduction tube of the character described, a tubular electrode, a lead-in wire fixed to one end of said electrode and supporting said electrode, and a hollow insulating member mounted on said lead-in wire and fitting loosely over the adjacent end of the electrode, said member having its exterior surface in close proximity to the tube wall whereby to prevent tilting of the electrode into contact with the tube wall.
- 20 5. In a gaseous conduction tube of the character described, a tubular electrode, a lead-in wire fixed to one end of said electrode and supporting said electrode, and a hollow insulating member mounted on said lead-in wire and fitting loosely over the adjacent end of the electrode, said member having its exterior surface in close proximity to the tube wall whereby to prevent tilting of the electrode into contact with the tube wall, said insulating member being apertured to receive the 10 lead-in wire and said lead-in wire being bent to hold the insulating member in place.
- 25 6. The electrode end of a gaseous conduction tube, comprising a length of glass tubing closed at one end, an elongated electrode in said tube, a lead-in wire fixed to the electrode, and a cup-shaped insulating member fitting over the lead-in wire and one end of the electrode, said cup-shaped member fitting loosely in the tubing and loosely over the electrode to allow for expansion 25 differences but holding the electrode away from the tube wall, the spacing of the cup-shaped member from the tube and from the electrode being small enough to prevent electrical discharge around the electrode to the lead-in wires.
